UNITED STATES PATENT OFFICE.

LUCIAN SYLVANUS SMITH, OF NICHOLASVILLE, KENTUCKY.

CAR-DOOR FASTENER.

1,251,124.

Specification of Letters Patent. Patented Dec. 25, 1917.

Application filed September 12, 1917. Serial No. 191,070.

To all whom it may concern:

Be it known that I, LUCIAN S. SMITH, a citizen of the United States, residing at Nicholasville, in the county of Jessamine 5 and State of Kentucky, have invented new and useful Improvements in Car-Door Fasteners, of which the following is a specification.

This invention relates to locks and latches, 10 and more especially to sliding door fasteners; and the object of the same is to produce a device of this type adapted particularly for use on freight car doors. The structure is such that the usual seal may be applied 15 to the fastener for one or both doors while the latter are still open, and when they are subsequently closed they become locked in such manner that they cannot thereafter be opened from the exterior without first 20 breaking the seal. The structure is also such, however, that either or both doors may be unfastened from the interior and opened without breaking the seal. Therefore the latter serves as a lock to the fastener only 25 after both doors have been closed and only then against a person on the outside of the car. For these reasons the invention is adapted particularly for use on freight car doors which slide open and closed, although 30 I do not wish to be limited in this respect.

Details are set forth below, and reference is made to the accompanying drawings wherein—

Figure 1 is a side elevation of part of a 35 freight car showing its door as closed and fastened by this improved device.

Fig. 2 is a similar view showing the keeper bar unlocked and dropped, the door in dotted lines partly open, and the latch 40 bar and latch, the latter in full lines as raised.

Fig. 3 is an inside elevation of a portion of the door, showing the latter in the act of closing and the latch as riding over the 45 keeper which is here raised.

Fig. 4 is a horizontal section on about the line 4—4 of Fig. 3.

Fig. 5 is a perspective detail of the latch and latch bar on an enlarged scale.

50 In the side of the ordinary freight car is a door opening O surrounded by a frame F hereinafter referred to as the frame element, and a track or hanger bar H extends along the top of the opening and the side of the 55 car, while a guide rail G extends along the bottom of the opening beneath said track,

a door D being suitably mounted thereon so that it may slide over the opening to close the same, or may be slid back to expose the opening as usual. This door D is herein- 60 after called the door element, but as above suggested it may be any door coacting with its frame element F in substantially the same manner shown. No novelty is claimed for the parts thus far described. I have 65 shown the door as made of sheet metal, and the frame as cut out with a recess R on its inner face in Fig. 3 to receive the latch when the door is closed, but these details are 70 unimportant.

Secured to the inner face of the door is a bar 1 having a double angle or elbow 2 in its body so that its front end, by which I mean that end toward the inner edge of the door, is spaced slightly therefrom as 75 seen at 3, and the bar is preferably of strap iron folded upon itself with its arms slightly spaced at the front end as seen in Fig. 5, so as to produce a bracket having an upright slot or opening for the reception of the 80 latch. The latter numbered 4 is a substantially triangular plate mounted on edge in said opening and pivoted at its front end at 5 within the arm 3, its rear upper corner having a finger 6 overlying and normally 85 resting on the elbow 2 by the gravity of the plate, and its lower edge 7 at this time extending below the front arm 3 of the bar and inclining downward from the pivoted front end of the latch toward its abrupt 90 rear end or heel 8.

Overlying the outside of the car body (or we might say of the frame element F) is a bar 10 pivoted at 11 to such element at its rear end, which is that end remote from the 95 door opening, its body being movable in an upright plane under a suitable guide 12 and its front end carrying a keeper 13 adapted to be engaged by the latch, for which purpose said keeper must stand in a plane trans- 100 verse to the upright plane in which the keeper plate moves. As perhaps the simplest manner of producing such keeper, I make the bar 10 of strap iron, extend its front end to and part way over the opening 105 O, and bend it sharply toward the interior of the car, preferably into a plane at right angles to that of the keeper bar 10; and the sheet metal door may be deflected outward slightly, as shown by the shading at 14 to 110 permit it to clear the front end of the bar as the door slides to its closed position. At

this time the front end 3 of the inner bar or bracket 1 and the latch 4 carried thereby stand within the recess R in the inner face of the frame element F as seen in Fig. 3—5 that is, unless the frame element also is of sheet metal and does not need to be cut away or recessed. However, when the door is closed the heel 8 of the latch is moved forward to a position beyond the plane of the keeper, and if now the keeper be raised it will pass behind said heel. When not raised, the keeper is not in the path of the latch even when the latter is in its lowest position. When the bar 10 and keeper 13 10 are raised and the door subsequently closed, the lower edge 7 of the latch travels over the keeper and causes the rise of the latch around its pivot, but when the door reaches its completely closed position the latch 15 drops into engagement with the keeper as will be clear. Therefore, to unfasten the device it is necessary either to drop the keeper which can be done from the exterior of the car by moving the bar 10 downward, 20 or to raise the latch which can be done only from the interior of the car.

Any suitable means may be provided for holding the keeper raised and in the path of the latch, but as herein shown I have 25 provided an ordinary hasp 20 loosely supported at its upper end on a staple 21 and having an eye 22 in its lower end adapted to pass over a stud 23 formed on the outside of the bar 10, the stud being perforated as 30 at 24 for the reception of a padlock or, as usual on freight car doors, a seal as indicated at S. The position of the staple and stud and length of the hasp are such that the locking means may only be applied 35 when the keeper bar and keeper are raised. The parts are by preference entirely of metal, suitably treated to prevent rust, and they occupy very little space, are inexpensive, devoid of springs, and not likely to 40 get out of order. If the door D be of wood, it may be recessed on its inner face instead of deflecting a sheet metal door outward as indicated at 14. In either case the purpose is to permit the door to slide open or closed 45 in an upright plane just outside that of and close to the frame, and yet provide as small space as possible for the passage of the front end of the bar 10 inside the door and its rise and fall.

50 55 In the operation of this device when applied to a freight car door as suggested, let us assume that the shipping agent desires to lock or seal the fasteners before the doors of a car are actually closed—the reason perhaps being that he is called away—and yet he does not care to leave with the workmen his locks or keys or the dies for impressing the usual seals S. It is only necessary for him to raise the keeper bars, engage the 55 hasps with their studs, and apply the locks

or seals to the perforations. Thereafter the loading of the car proceeds as usual, and when it is finished the door or doors are slid closed. This causes the latches to ride over the keepers and their heels to drop into engagement therewith. If one door should be closed prematurely, or if both doors should be closed while the workmen are yet within the car, it is possible for them to lift the latch by grasping its finger, and then 75 slide open the door; but once both doors are closed and fastened and there is no possibility of any one gaining access to the inner side of the door, the same can not be unlatched except from the exterior and then 80 only by first removing the lock or seal. Thus the car travels to its destination, and the receiving agent unlocks it from the exterior, when the front end of the keeper drops to the position shown in Fig. 2 and 85 the keeper passes out of the path of the latch, so that thereafter the door may be slid open from the exterior.

Usually the shipping agent closes and seals the door at the last moment before 90 starting the car on its journey, and my invention in no way interferes with this custom. Other advantages result from the use of a fastener of this type. I might mention as one that, if the car contained valuable freight such as bullion and it were desired to have an attendant travel with it as a guard, he could be put into the car and the doors fastened and very strongly padlocked so as to exclude possible highwaymen, and yet the guard could make his exit whenever he desired. He might in fact be the express agent of a way train running through a dangerous country, and yet at 95 each station he could open either door from 100 the interior although at no time could any one open the door from the exterior without first removing the seal or padlock.

What is claimed is:

1. In a fastener of the type described, 110 the combination with fixed and movable elements; of a latch pivotally supported on the movable element and normally standing with its lower edge inclined toward its rear end, a bar on the fixed element swinging in 115 an upright plane, a keeper at the free end of the bar normally standing below the path of the latch, and means for raising such free end to bring the keeper into said path and locking it in such position.

2. In a fastener of the type described, the combination with fixed and movable elements; of a latch pivotally mounted on the inside of one element and inaccessible from the exterior, its lower edge normally standing inclined, a support pivotally mounted on the exterior of the other element and carrying a keeper over which the movable element closes, the keeper standing normally below the path of said lower edge, 120 125 130

and means accessible from the exterior for raising the keeper into said path and locking it there.

3. In a sliding door fastener, the combination with fixed and movable elements; of a bracket secured inside one element and having an elbow within its length, a latch pivoted at its front end in said bracket with its lower edge normally inclined to its heel and its upper corner having a finger resting on said elbow, a bar pivoted at its rear end to the outside of the other element and bent at its front end into a keeper adapted to enter behind the edge of the first element, a guide for permitting the rise and limiting the fall of the bar and keeper to a position normally below the path of the lower edge of the latch, and means for locking said bar and keeper when raised. 15
10 In testimony whereof I affix my signature. 20

LUCIAN SYLVANUS SMITH.
